UNITED STATES PATENT OFFICE.

PETER MCLEAN, OF WELLAND, ONTARIO, CANADA.

ROTARY PUMP.

Application filed September 5, 1922. Serial No. 586,284.

To all whom it may concern:

Be it known that I, PETER MCLEAN, a subject of the King of Great Britain, residing at Welland, in the Province of Ontario and Dominion of Canada, have invented certain new and useful Improvements in a Rotary Pump, of which the following is a specification.

This invention relates to an improved type 10 of rotary pump, designed to prevent entrance of air into the pump under working of the same.

The primary object of this invention is the provision of a durable type of rotary 15 pump including an improved rotor arrangement whereby a liquid is drawn into a stator and forced toward a gland end of the same under pressure so that the liquid may have an exit from the stator adjacent the gland 20 end of the stator, and thereby preventing entrance of air through the gland end to the stator.

A further object of the invention is the provision of an improved means for supporting the rotor in pumps.

Other objects and advantages of this invention will be apparent during the course of the following detailed description.

In the accompanying drawing, forming a 30 part of this specification, and wherein similar reference characters designate corresponding parts throughout the several views;

Figure 1 is a longitudinal cross sectional view, taken through the improved pump arrangement, and showing cooperating details thereof.

Figure 2 is a transverse cross sectional view, taken substantially on the line 2—2 of Figure 1.

Figure 3 is a transverse cross sectional view, taken substantially on the line 3—3 of Figure 1.

Figure 4 is a fragmentary plan view of the improved pump, showing in particular 45 the stator arrangement thereof.

In the drawing, wherein for the purpose of illustration is shown but the preferred embodiment of this invention, the letter A designates the improved pump arrangement 50 which embodies a support arrangement B; stator C; and rotor D.

Referring to the stator arrangement C, the same includes a housing 10 which is preferably rectangular in exterior formation 55 and is provided with a cylindrical straight bore 11 therethrough. Inlet and

outlet openings 16 and 16^a respectively are preferably provided through the housing 10 adapted to receive inlet and outlet pipes 12 and 13 respectively, said pipes being 60 disposed adjacent opposite ends of the housing 10. The end 15 is provided for the housing 10 adapted for detachable connection to the end of said housing adjacent its inlet opening 16 and the pipe 12 which cooperates in said opening 16. This end 15 is provided with a cylindrical shaped extension 17 upon the inner portion thereof of which is adapted for snug fitting in the bore 11 of the housing 10; a flange portion 70 19 extending peripherally about the cylinder inserting portion 17, and which is adapted for overlying the outer marginal end of the housing 10 adjacent the inlet pipe 12. A gasket 20 is preferably provided for co-operation intermediate the flange portion 19 and the outer marginal end surface of the housing 10. A plurality of bolts 21 are preferably provided for connecting the end 15 to the housing 10. A portion 22 may be 75 provided extending outwardly of the part of the attaching end 15 and is provided with a socket depression 23 opening inwardly and aligning axially with the bore 11 of the housing 10, and in which the extreme end 24 of the rotor shaft 25 is adapted for bearing. An anti-friction bearing is preferably provided in this depression 23, which may be in 80 the form of a ball bearing 26 seated in arcuate depressions 27 and 28^a in the facing end 85 surfaces of the shaft 25 and socket depression 23. For lubricating purposes, a detachable screw or bolt member 28 is preferably provided, extending laterally and radially through the projecting portion 22 of the end 90 15, and which includes a non-leak washer connection 29, whereby lubricant may be fed into the socket opening 23 through the opening 30 in which said detachable screw member 28 cooperates.

A head 32 is preferably provided upon the opposite end of the housing 10 and which has a bore 33 extending axially therethrough into which the shaft 25 extends and in which the same bears. The end 32 is counterbored and provided with a packing gland 35, whereby the connection of the shaft 25 with the bore 33 may be rendered leak proof. The head member 32 is preferably provided with a ring shaped portion 35^a which is 100 adapted for cooperation in the rotor arrangement D in a manner to be subse- 105 110

quently set forth. A portion 36 of the end 32 fits into the housing bore 11 in snug relation, so that the flange portion 37 of the end 32 overlies the end surface of the housing 10; a gasket 38 cooperating intermediate the facing surfaces of the flange 37 and the housing 10 to provide a non-leak connection.

Bolts 39 are preferably provided for attachment of the end 32 to the housing 10. The gland 35 may be attached in the end 32 as by the adjustable nuts 41.

Referring to the rotor arrangement D, the shaft 25 is a part thereof, and as before stated has a dead end 24 thereof bearing within the socket depression 23 of the stator end 15. An end 42 of said shaft 25 extends exteriorly of the head 32 of the stator C and bears in a babbitt bushing 43 of a standard 44. The rotor member 45, which extends longitudinally in the bore 11 of the stator housing 10 is of novel formation, and includes the cylindrical portion 46 provided with the longitudinal bore 47 through which the shaft 25 extends. Tapered passageways 49 and 50^a are respectively provided in the portion 46 of the rotor 45 and the shaft 25, which are adapted for receiving a tapered locking pin 51, whereby the rotor 45 may be connected to the shaft 25 for rotation therewith. The rotor 45 furthermore includes a plurality of spiral shaped blades 50 which extend about the casing portion 46 and are disposed in overlapping relation. Thus, it can be seen that the rotor 45 is of the worm or screw type with the blades 50 thereof relatively formed on an overlapping pitch. The end of the rotor 45 adjacent the head 32 of the stator C, is preferably provided with an annular seat 53 in which the inwardly extending collar 35^a of the head 32 seats, to have an additional safeguard against seeping of liquid exteriorly of the stator C.

The rotor 45 when disposed within the chamber 11 of the housing 10 provides a chamber or compartment 70 intermediate the facing surfaces of the rotor 45 and the end member 15 which extends annularly about the shaft 25. The inlet opening 16 and the pipe 12 communicate with this compartment 70, so that during rotation of the rotor 45, the liquid or other material may be drawn into the compartment 70 so that the same may flow between all of the passageways intermediate adjacent spiral blades 50. Similarly a compartment 71 is annularly provided about the sleeve extension 35^a intermediate the facing surfaces of the rotor 45 and the head 32. The outlet opening 16^a as well as the outlet conduit 13 communicates with the compartment 71, whereby liquid may be supplied to the compartment 71 from all of the passageways intermediate the blades 50 of the rotor 45,

and thereby the liquid in said compartment 71 may flow into the outlet conduit 13.

The stator C includes the base 60 upon which the supporting blocks or pillars 61 rest and through which the bolts 62 extend for engagement in the housing 10, whereby the stator C may be securely clamped to the base 60. The standard 44 above mentioned, may likewise be attached as by bolts 63 to the base 60. A drive pulley 65 may be keyed as at 66 to the outwardly extending portion 42 of shaft 25. If desired, an idler pulley 67 may be provided upon the shaft 25, being loosely disposed thereon intermediate the sleeves 68, which are keyed to shaft 25.

During operation the thrust incident to drawing and forcing of the liquid through the stator C will be upon the end arrangement 15 of the stator C, and in particular upon the anti-friction bearing 26. This bearing 26 in the smaller type of pump may be a single ball bearing, although it is preferred in the larger pumps, that a ring of thrust bearings be provided. In view of the fact that the end 15 of the pump A is solid and supports the extreme end 24 of the shaft 25, therein in the dead end bearing, there is little likelihood of leak or seepage of air in the stator housing 10 incident to sucking force of the blades 50. The course of the liquid will be more particularly directed to the head 32 of the pump A, and thus the pressure upon said head will be from the interior of the stator A, so that it will be seen that no air whatsoever can enter from this head 32.

From the foregoing description of this invention, it can be seen that a very durable and effective type of rotary pump has been provided, in which the parts thereof so co-operate during operation that there is practically no likelihood of entrance of air for mixture with a liquid being pumped. The desirability of such arrangement can be well understood by those versed in the art to which this invention pertains.

Various alterations in the shape, size and arrangement of parts may be made to the form of the invention herein shown and described, without departing from the spirit of the invention or the scope of the claim.

I claim:

A rotary pump comprising a cylindrical casing open at its end and adjacent one end having a side port for the admission of fluid and adjacent its other end having a side port for the outlet of fluid, a head closing one end of said casing and having a socket leading from its inner face exteriorly of the casing, a shaft extending into the casing through the other end thereof and having an end portion rotatably fitting in the pocket of said head, a rotor mounted upon said shaft to turn with the shaft and positioned in the casing with one end terminating in

spaced relation to the inner face of said head, the other end of said rotor having an annular pocket about said shaft, a closure head for the second open end of said casing fitting about said shaft with its inner face in spaced relation to the end of the rotor, the second head being provided with an annular sleeve fitting about the shaft and ex- tending into the pocket formed in the end portion of said rotor, the last mentioned head being provided with a packing receiving pocket leading from its outer face about the shaft, and a packing gland for compressing packing in the packing receiving socket.

PETER McLEAN.
